DOLL EYE MOUNTING

Morris Buchner and Max Kapp, Bronx, N. Y.

Application September 15, 1939, Serial No. 294,994

3 Claims. (Cl. 46—165)

The purpose of this invention is to provide an improvement in devices for mounting doll eyes in doll heads by which the eyes are permanently secured in place.

5 The invention is a doll eye mounting of the type having the eyes mounted on pins, in which the pins are forced into the head for holding the eyes in place, and in which the pins are formed with barbs or projections preventing removal of 10 the eyes.

Doll eyes of this type have normally been formed with caps forming a base with liners therein, and a Celluloid cover at the front, with the pupils either printed on the liner or freely positioned therein, and the cap forming the base has been provided with a straight pin riveted or soldered therein, so that the pin may be forced into the doll head, and, although these are cemented, the pins work loose so that the eyes drop 15 out or children pull them out, and the eyes with the pins are objectionable because many children have been injured thereby, after removing them from the dolls.

The object of this invention is, therefore, to 20 improve mountings of this type so that once the eyes are driven in place they cannot be removed without substantially tearing the head into parts.

A further object is to provide pins for doll eye 25 mountings with barbed surfaces to prevent removal.

And a still further object is to provide doll eye 30 mountings which positively prevent removal of the eyes which are of a simple and economical construction.

35 With these ends in view the invention embodies doll eyes having covers with bases, and barbed pins secured in the bases and extended backward therefrom.

Other features and advantages of the invention 40 will appear from the following description taken in connection with the drawing, wherein:

Figure 1 is a view showing a doll eye with a pin having barbed edges.

Figure 2 is a view showing a front elevation 45 of an eye of this type.

Figure 3 is a cross section through the pin.

Figure 4 is a view looking toward the back of the eye.

Figure 5 is a detail showing the pin in elevation with a cross section through the head showing the mounting of the pin therein.

Figure 6 is a detail showing the head of the pin.

Figure 7 is a detail showing a cross section through a pin of an alternate design in cross 55 section.

Figure 8 is a similar view showing another alternate design in which the pin is square.

Figure 9 is a similar view showing a round pin.

Figure 10 is a similar view showing a pin of a triangular shape.

Figure 11 is also a similar view showing a pin 5 bent at the middle forming an L-shape or triangle.

Figure 12 shows another alternate method of 10 forming the pin or prong in which it is semi-circular in cross section with the barbs extruded therefrom.

In the drawing the mounting is shown as it 15 may be made, wherein numeral 1 indicates the pin, numeral 2, the cup forming the base of the eye, and numeral 3, the transparent cover of the eye.

The pin or shank 1 is formed of a flat piece of 20 material with barbs 4 at the sides, and in the design shown in Figures 3 and 5, it is indented forming a groove 5 providing reinforcing and 25 adding sufficient strength to enable the shank or pin to be forced into the material forming the head of a doll without bending, and, at the same time, making it possible to use a relatively thin 30 material.

The head of the pin is held in a slot 6 of the 35 cap 2, and, although it may be secured therein in any manner, or by any means, it is bifurcated, forming two projections 7 and 8, one of which 40 is bent in one direction and the other backward, thereby riveting the head of the pin in the base, and the pin may be provided with a shoulder 9 against which the base is held by the projections. In the design shown in Figure 1, the eye is provided with a pin 10 having barbs 11, and the pin is secured in the base 12 of the eye 45 13 either as shown in Figure 5 or in any manner.

The pin or shank may be provided with a 50 groove 5, as shown in Figures 3 and 5, or the shank may be straight, as shown in Figure 1, or it may be of any shape in cross section, as 55 illustrated in Figures 7 to 11, the shank 14 being elliptical in Figure 7, and provided with barbs 15, square in Figure 8 in which it is indicated by the numeral 16 and provided with barbs 17 at the corners, round as shown in Figure 9 in which the shank is indicated by the numeral 18, and this is provided with barbs 19, or triangular as shown in Figure 10, in which it is indicated by the numeral 20 and provided with barbs 21. Figure 11 is similar to that shown in Figure 3 except that the material of the pin or shank is 60 bent in the form of an L or triangle, the material being indicated by the numeral 22, and this 65

is provided with barbs 23, and in Figure 12 the pin 24 is substantially semicircular with the barbs 25 extruded or stamped therefrom.

It will be understood that other changes may be made without departing from the spirit of the invention. One of which changes may be in the use of the barb pin or the shank with the eye of any other type or design, another may be in the use of other means for holding the pin or shank in the eye, and still another may be in the use of other means for providing barbs on the pin.

The construction will be readily understood from the foregoing description. In use the eye 15 may be provided as shown and described, and it will be noted that, when installing the eye in the head, the barbed shank may be forced into the head, and, once it is in place, it would be substantially impossible to remove it. It may be 20 further secured by cement if desired, however with the barbed shank as shown and described, a cement is not necessary.

The barbed shank is illustrated as having only several barbs on each side, and with the barbs 25 relatively large however, for relatively compact or solid doll heads, comparatively small barbs, corrugations, projections, or teeth may be used, and any number of barbs may be employed.

Having thus fully described the invention, what we claim as new, and desire to secure by Letters Patent is:

1. An attachable doll feature comprising a base and a prong mounting means, the head of the prong being bifurcated, the said bifurcated portions adapted to pass through an opening in the base and then bent in opposite directions, a shoulder adjacent the bifurcated parts against which the base is secured by the said bifurcated 10 parts.

2. An attachable doll feature as described in claim 1, characterized by barbs on the prong.

3. A doll eye comprising a base with a cover 15 extending from the rear of the base providing the mounting means therefor, said device characterized in that the head of the prong is bifurcated with a shoulder against which the base is secured by the said bifurcated parts with the 20 bifurcated parts bent in opposite directions, and further characterized in that the edges of the prong are formed with barbs preventing removal of the eye from an object in which it may be inserted.

MORRIS BUCHNER.
